FURNACE FLUE DAMPER

Hal M. Cunningham, New Britain, Conn.

Application November 7, 1939, Serial No. 303,228

14 Claims. (Cl. 236—45)

This invention relates to dampers, and especially to flue dampers for furnaces either of the domestic or of commercial or industrial types.

One of the primary objects is to improve combustion by accurate control of draft, the damper of the present invention being fully automatic in its operation.

More specifically, it is an object of the invention to provide substantially uniform furnace draft, notwithstanding fluctuations in flue temperature and other variable factors, such as wind direction and velocity, all of which usually have marked influence on furnace draft.

The nature, objects and advantages of the invention, as well as the operation of my improved damper, can be discussed to best advantage with reference to a typical domestic furnace installation adapted to the burning of oil.

In such oil burning installations, the oil is customarily fed in measured quantities by a pump, or equivalent means. Naturally, for efficient and perfect combustion of a given quantity of oil, an exact predetermined quantity of air is required.

With air supplied to the combustion chamber in whole or in part under the influence of chimney draft, the quantity of air admitted to the combustion chamber obviously varies in accordance with a number of factors, such as those mentioned above (for example, flue temperature) and in consequence, in installations of this type, in the absence of some control of the draft, imperfect and inefficient combustion takes place throughout most, if not all, of the time the furnace is in operation.

The problem in a domestic installation (and also in numerous commercial and industrial installations) is further complicated by the fact that, for economic reasons, the operation is ordinarily intermittent, resulting in repeated changes in flue temperature and other conditions throughout each day.

Numerous dampers have been proposed heretofore for this purpose but they have been found ineffective in control, irregular in operation, and inadequate to provide efficient combustion. The present invention provides a damper which is fully automatic and which maintains a very high degree of uniformity in draft under widely varying conditions.

In general, the improved damper of the present invention comprises a gate adapted to be mounted in the aperture or opening in the flue running from the furnace to the chimney or stack, the gate serving to admit more or less air into the flue, in accordance with increases and decreases in chimney draft, thereby maintaining uniform admission of air into the combustion chamber through the openings provided for that purpose.

The manner in which the objects and advantages of the invention are carried out will be further apparent from the following description, referring to the accompanying drawing, in which—

Figure 1 is a plan view of a portion of a flue pipe having an opening therein equipped with the improved damper of this invention, the damper being shown in section as indicated by the section line 1—1 on Figure 2;

Figure 2 is an enlarged inner elevational view of the damper;

Figure 3 is a vertical sectional view taken as indicated by the line 3—3 on Figure 2;

Figures 4 and 5 are diagrammatic views similar to the showing of Figure 3 but illustrating the gate in different positions; and

Figure 6 is a view similar to Figure 3 but illustrating a modified arrangement.

In Figure 1 the flue appears at 1, the direction of gas flow therein being shown by the arrows, the portion *a* of the flue being extended to the combustion chamber and the portion *b* to the stack. The flue is apertured and provided with a transverse branch 8 adapted to receive the damper. The damper includes a flanged frame 9 adapted to fit and cooperate with the mouth of the branch 8. The frame, and also the gate 10, are shown as being circular, although other shapes may be employed if desired.

The gate itself takes the form of a circular sheet metal plate which is desirably reinforced by an angle 11 positioned approximately diametrically thereof and also by a pair of additional angle members 12, 13 and 14—14.

Toward opposite ends of angle member 11, a pair of pivot devices 15—15 are secured to the gate and project in opposite directions beyond the edge of the gate to cooperate with pivot bearings mounted within bearing straps 16—16.

carried by the frame 9, and serving to pivotally mount the gate for movement to open and close the mouth of the flue branch 8. The pivot axis for the gate need not necessarily be mounted horizontally, it being permissible with the arrangement shown to incline the axis to as much as 45° or more on either side of the horizontal position. In many instances inclined mounting of the axis is effective to improve the character of the draft control.

In any event, it will be seen that the gate is mounted so that in closed position the inner face of the gate is subject to flue pressure or draft action, the outer face being exposed to atmosphere.

In contrast with most prior damper arrangements, the damper of the present invention is provided with a pivot axis which is located diametrically substantially at the center of the damper to provide gate areas at opposite sides which, when the gate is in closed position, are in substantial aerostatic balance. Thus, in the absence of some means upsetting this balance, the gate would not open under the influence of differential pressure as between the zones inside of and outside of the gate. For reasons brought out more fully hereinafter, I prefer to employ a gate having the aerostatic balance referred to, the action thereof being more accurate in various positions of the gate.

However, in order to provide for automatic opening of the gate upon a predetermined increase in draft, the invention provides a means for upsetting the normal aerostatic balance when the gate is at or near closed position. This means includes an air chamber formed in part by baffle wall 17 which is secured to the inner edge of the flange of frame 9 and which has an edge 18 bent toward the gate, as clearly appears in Figures 2 and 3. When the gate is in full closed position, therefore (see Figure 3) a chamber 19 is formed adjacent the inner face of an upper portion of the gate area. This chamber has relatively free communication with atmosphere through the parti-annular space between the edge of the gate and the frame 9, as indicated at 20 in Figure 3. The chamber, on the other hand, has relatively restricted communication with the interior of the flue. In consequence, the pressure in the chamber 19 and at the adjacent portion of the inner face of the gate remains closer to atmospheric pressure than does the pressure in the flue and adjacent the remainder of the inner face of the gate.

The above provision upsets the aerostatic balance of the gate, in consequence of which, the lower edge thereof will be moved inwardly (for example, to the position shown in Figure 4) upon drop in flue pressure (increase in draft) to a predetermined value. The foregoing pressure condition is maintained (at least in part) throughout a substantial portion of the opening movement from full closed position. The effectiveness of the chamber, however, decreases, especially after reaching the position of Figure 4, in which the free edge of angle member 12 is just about to leave its position of close proximity to the flange 18 forming the lower edge of the air chamber. The action of the air chamber substantially completely disappears about or a little beyond the position of the gate shown in Figure 5, i. e., at a gate position of about 30°-40°.

Continued opening movement of the gate will now take place with further pressure reduction in the flue (further increase in draft) under the

aerodynamic action of the air entering the flue and striking the lower half of the gate which is moving into the flue branch 8. Under this action the gate will move anywhere up to the full open position, depending upon the draft condition, the opening movement being assisted by some aerostatic unbalance at opposite faces of that portion of the gate which swings into the flue opening.

10 The aerostatic and aerodynamic moments tending to open the gate may be opposed either by employing spring means urging the gate toward closed position or by weighting of the gate. If spring means be employed, they should preferably be arranged to provide approximately uniform closing force substantially throughout the entire range of movement of the gate.

15 In the embodiment illustrated, weighting is illustrated for effecting closing movement of the gate. For this purpose I prefer to employ a weight of the type indicated at 21, constituting a knurled nut threaded on a screw 22 which, in turn, is fastened to the gate by slightly spreading and deforming the upstanding portions of angle members 14-14 to form a socket 23 in which the screw 22 engages.

20 The position of the weight may readily be adjusted throughout a substantial range because of the extended screw thread 22, and thereby the 25 damper may be adjusted to give the desired draft notwithstanding varying conditions encountered in different installations. In all positions of adjustment, however, it will be noted that the weight is so located with reference to the pivotal

30 axis and to the gate area that a closing force is provided under the influence of gravity throughout the entire range of gate movement between full closed and full open positions. The particular location of the weight is further of im-

35 portance in maintaining the accuracy of draft control herein contemplated. Note, for example, that in full closed position the position of the weight is such that its effect is noticeably less than maximum, the maximum effect being se-40

45 cured when the weight projects horizontally as in Figure 5. In the range of gate movement in the neighborhood of Figures 4 to 5 (when the closing force of the weight reaches its maximum), the fin 12 which is desirably made of sub-50 stantial width, aids in maintaining the action of the air chamber and thus in maintaining the opening force at a value sufficiently high to avoid any undesirably abrupt increase in draft in the furnace. As the gate approaches its full open

55 position, the weight again loses some effectiveness, and with this in mind the upstanding portion of angle member 13 is so proportioned that the air entering the flue along the upper side of the gate strikes the angle member and contrib-60 utes an additional aerodynamic moment tending to move the gate toward closed position.

A stop member 22a is arranged to cooperate with the screw 22 to limit opening movement of the gate.

65 From the foregoing it will be noted that the forces tending to open the gate are in part aerostatic and in part aerodynamic, the former predominating in full closed position and the latter predominating after the gate has moved substantially from the full closed position. By careful arrangement of the parts, as above outlined, and as illustrated, it will be found that an unusual degree of uniformity in draft may be secured in the combustion chamber, notwithstanding wide 70 variations in the flue. By way of illustration,

pressure readings were taken under various conditions, showing the following results (all figures in hundredths of an inch of water pressure drop).

In one test the draft was increased in the chimney end (b) of the flue, as shown in Figure 1, throughout a range from 1 to 15 and then pressure drop readings were taken in the flue at end a, showing the following results:

Test 1

(Gate set to hold draft at .045")

Draft at a with gate held in closed position	Draft at a with gate free	Variation from desired value
Inches	Inches	Inches
.05	.0425	.0025
.12	.045	.00
.15	.045	.00

In another test, an even wider range of draft fluctuation was tested, giving the following readings:

Test 2

(Gate set to hold draft at .035")

Draft at a with gate held in closed position	Draft at a with gate free	Variation from desired value
Inches	Inches	Inches
.05	.035	.00
.10	.04	.005
.15	.035	.00
.21	.04	.005

From the foregoing it will be seen that even with wide fluctuations in the chimney draft, the draft through the combustion chamber varies very little indeed from the desired value.

For purposes of comparison and information, one of the currently most widely used prior art dampers was given each of the two tests above under identical conditions, with the following results:

Test 1

(Gate set to hold draft at .045")

Draft at a with gate held in closed position	Draft at a with gate free	Variation from desired value
Inches	Inches	Inches
.05	.045	.00
.12	.09	.045
.15	.10	.055

Test 2

(Gate set to hold draft at .035")

Draft at a with gate held in closed position	Draft at a with gate free	Variation from desired value
Inches	Inches	Inches
.05	.035	.00
.10	.06	.025
.15	.11	.075
.21	.145	.11

While I prefer the damper arrangement above described, certain features of the invention are also applicable to a damper having an off center pivot mounting, i. e., one in which the gate is not aerostatically balanced when in full closed position. A gate of this type appears in the showing of Figure 6 as applied to a flue branch 8, the

70
75

damper including a frame 9a acting as a support for the gate 10a having an off center pivot 15a. In this arrangement an aerostatic unbalance normally serves to effect opening movement of the gate, the closing movement being effected under the influence of gravity. For the closing movement, either the unbalance in weight normally provided by offsetting the pivot may be relied upon, or the gate may be equipped with a supplemental weight or spring.

As shown in Figure 6, an air chamber is provided by a member 24 cooperating with the outer face of the gate at the side of the pivot 15a on which lies the larger gate area. The chamber 15 has relatively free communication with the interior of the flue through a slot or aperture 25, so that in closed position, a portion of the outer face of the gate is subjected to a pressure lower than atmospheric. This tends to resist the initial 20 opening movement of the gate which is advantageous in the type of damper illustrated in Figure 6, since one defect of that type is its tendency to commence opening movement too readily under the influence of even a small drop in flue pressure. 25 Thus, the feature of my invention providing for use of an air chamber for transferring the pressure condition at one face of the gate to a portion of the other face thereof, may also be employed in a damper of the type illustrated in 30 Figure 6 for the purpose of smoothing out the draft and thereby improving efficiency and uniformity of combustion.

I claim:

1. A furnace flue damper including a gate having pivot means for mounting it in a flue opening for movement to open and close the flue opening, the gate in closed position being exposed to a zone of atmospheric pressure on its outer face and to a zone of flue pressure on its inner face, the 40 pivotal axis being positioned to provide gate areas at opposite sides of the axis in substantial aerostatic balance, means cooperating with the gate in closed position to form a chamber adjacent the inner face of the gate toward one side of the 45 pivotal axis, which chamber, with the gate at or near closed position, has relatively free communication with the pressure zone adjacent the outer face of the gate but restricted communication with the pressure zone adjacent the inner face 50 thereof, whereby to upset said aerostatic balance and provide for opening of the gate under the influence of a pressure drop in the flue, and means normally urging the gate toward closed position.

2. A furnace flue damper including a gate having pivot means for mounting it in a flue opening for movement to open and close the flue opening, the gate in closed position being exposed to a zone of atmospheric pressure on its outer face and to a zone of flue pressure on its inner face, the 60 pivotal axis being positioned to provide gate areas at opposite sides of the axis in substantial aerostatic balance and further to provide for movement of a portion of the gate into the flue opening and of another portion thereof out of 65 the flue opening as the gate moves from closed toward open position so that the flow of air entering the flue after the gate has moved substantially from closed position acts aerodynamically on the gate to move the gate further toward open position, means cooperating with the gate in closed position to form a chamber adjacent the inner face of the gate toward one side of the pivotal axis, which chamber, with the gate at or near closed position, has relatively free communication with the pressure zone adjacent the

outer face of the gate but restricted communication with the pressure zone adjacent the inner face thereof, whereby to upset said aerostatic balance and provide for opening of the gate under the influence of a pressure drop in the flue, and means normally tending to urge the gate toward closed position in opposition to the force tending to open the gate aerodynamically.

3. A furnace flue damper including a gate having pivot means for mounting it in a flue opening for movement to open and close the flue opening, the gate in closed position being exposed to a zone of atmospheric pressure on its outer face and to a zone of flue pressure on its inner face, the pivotal axis being positioned to provide gate areas at opposite sides of the axis in substantial aerostatic balance, and means cooperating with the gate in closed position to form a chamber adjacent the inner face of the gate toward one side of the pivotal axis thereof, which chamber, with the gate at or near closed position, has relatively free communication with the pressure zone adjacent the outer face of the gate but restricted communication with the pressure zone adjacent the inner face thereof, whereby to upset said aerostatic balance and provide for opening of the gate under the influence of a pressure drop in the flue.

4. A furnace flue damper including a gate having pivot means for mounting it in a flue opening for movement to open and close the flue opening, the gate in closed position being exposed to a zone of atmospheric pressure on its outer face and to a zone of flue pressure on its inner face, the pivotal axis being positioned to provide gate areas at opposite sides of the axis in substantial aerostatic balance and further to provide for movement of a portion of the gate into the flue opening and of another portion thereof out of the flue opening as the gate moves from closed toward open position so that the flow of air entering the flue after the gate has moved substantially from closed position acts aerodynamically on the gate to move the gate further toward open position, means cooperating with the gate in closed position to form a chamber adjacent the inner face of the gate toward one side of the pivotal axis thereof, which chamber, with the gate at or near closed position, has relatively free communication with the pressure zone adjacent the outer face of the gate but restricted communication with the pressure zone adjacent the inner face thereof, whereby to upset said aerostatic balance and provide for opening of the gate under the influence of a pressure drop in the flue, and means normally tending to urge the gate toward closed position in opposition to the force tending to open the gate aerodynamically.

5. A furnace flue damper including a gate having pivot means for mounting it in a flue opening for movement to open and close the flue opening, the gate in closed position being exposed to a zone of atmospheric pressure on its outer face and to a zone of flue pressure on its inner face, the pivotal axis being positioned to provide gate areas at opposite sides of the axis in substantial aerostatic balance and further to provide for movement of a portion of the gate into the flue opening and of another portion thereof out of the flue opening as the gate moves from closed toward open position so that the flow of air entering the flue after the gate has moved substantially from closed position acts aerodynamically on the gate to move the gate further toward open position, and means cooperating with

5 the gate in closed position to form a chamber adjacent the inner face of the gate toward one side of the pivotal axis thereof, which chamber, with the gate at or near closed position, has relatively free communication with the pressure zone adjacent the outer face of the gate but restricted communication with the pressure zone adjacent the inner face thereof whereby to upset said aerostatic balance and provide for opening of the gate under the influence of a pressure drop in the flue, the gate being weighted in a sense tending to move the gate about its pivotal axis from open toward closed position in opposition to the force tending to open the gate aerodynamically.

6. A furnace flue damper including a gate having pivot means for mounting it in a flue opening for movement to open and close the flue opening, the pivotal axis being positioned to provide gate areas at opposite sides of the axis in substantial aerostatic balance and further to provide for movement of a portion of the gate into the flue opening and of another portion thereof out of the flue opening as the gate moves from closed toward open position so that the flow of air entering the flue after the gate has moved substantially from closed position acts aerodynamically on the gate to move the gate further toward open position, and means operative at or near closed position for upsetting said substantial aerostatic balance to effect initial opening movement of the gate, and the gate being weighted to provide a closing force in opposition to the force tending to open the gate aerodynamically.

7. A furnace flue damper in accordance with claim 1, in which the means normally urging the gate toward closed position has a closing force which is different in different positions of the gate, being at a maximum at a point approximating the mid point between full open and full closed positions.

8. A furnace flue damper in accordance with claim 6, further characterized by the provision of a fin projecting from the inner face of the portion of the gate which moves into the flue upon opening movement, the fin being positioned at that side of the pivotal axis providing an aerodynamic moment tending to close the gate under the influence of airflow entering the flue opening.

9. A furnace flue damper in accordance with claim 6, further characterized by the provision of a fin projecting from the inner face of the portion of the gate which moves into the flue upon opening movement, the fin being positioned at that side of the pivotal axis providing an aerodynamic moment tending to close the gate under the influence of airflow entering the flue opening and further arranged so that the maximum aerodynamic moment tending to close the gate is secured adjacent the full open end of the range of movement of the gate.

10. A furnace flue damper including a frame adapted to be mounted in a flue opening, a gate pivotally mounted in said frame for movement to open and close the flue opening, the gate in closed position being exposed to a zone of atmospheric pressure on its outer face and to a zone of flue pressure on its inner face, the pivotal axis being positioned to provide gate areas at opposite sides of the axis in substantial aerostatic balance and further to provide for movement of a portion of the gate into the flue opening and of another portion thereof out of the flue opening as the gate moves from closed toward open position so that the flow of air entering the flue after the gate has moved substantially from closed position

acts aerodynamically on the gate to move the gate further toward open position, and means carried by said frame and forming an air chamber adjacent the inner face of the portion of the gate area which moves out of the flue during opening movement, said chamber, with the gate at or near closed position, having relatively free communication with the pressure zone adjacent the outer face of the gate but restricted communication with the pressure zone adjacent the inner face thereof, whereby to upset said aerostatic balance and provide for opening of the gate under the influence of a pressure drop in the flue.

11. A furnace flue damper including a gate having pivot means for mounting it in a flue opening for movement to open and close the flue opening, the gate in closed position being exposed to a zone of atmospheric pressure on its outer face and to a zone of flue pressure on its inner face, the pivotal axis being positioned to provide gate areas at opposite sides of the axis in substantial aerostatic balance and further to provide for movement of a portion of the gate into the flue opening and of another portion thereof out of the flue opening as the gate moves from closed toward open position so that the flow of air entering the flue after the gate has moved substantially from closed position acts aerodynamically on the gate to move the gate further toward open position, and means cooperating with the gate in closed position to form an air chamber adjacent the inner face of the portion of the gate area which moves out of the flue during opening movement, said chamber, with the gate at or near closed position, having relatively free communication with the pressure zone adjacent the outer face of the gate but restricted communication with the pressure zone adjacent the inner face thereof, whereby to upset said aerostatic balance and provide for opening of the gate under the influence of a pressure drop in the flue.

12. A furnace flue damper including a frame adapted to be mounted in a flue opening, a gate pivotally mounted in said frame for movement to open and close the flue opening, the gate in closed position being exposed to a zone of atmos-

pheric pressure on its outer face and to a zone of flue pressure on its inner face, the pivotal axis being positioned to provide gate areas at opposite sides of the axis in substantial aerostatic balance and further to provide for movement of a portion of the gate into the flue opening and of another portion thereof out of the flue opening as the gate moves from closed toward open position so that the flow of air entering the flue after the gate has moved substantially from closed position acts aerodynamically on the gate to move the gate further toward open position, and baffle means associated with the frame and with the gate and cooperating to form a chamber adjacent one face of the gate toward one side of the pivotal axis, which chamber, throughout an initial portion of the opening movement has relatively free communication with the pressure zone adjacent the other face of the gate but restricted communication with the pressure zone adjacent said one face thereof, whereby to upset said aerostatic balance and provide for opening of the gate under the influence of a pressure drop in the flue.

13. A furnace flue damper including a gate adapted to be pivotally mounted in a flue opening for movement to open and close the flue opening, the pivotal axis extending across the gate area in a central region thereof, the gate in closed position being exposed to a zone of atmospheric pressure on its outer face and to a zone of flue pressure on its inner face and being movable toward open position under the influence of an increase of flue draft and toward closed position under the influence of a decrease in flue draft, and means forming a chamber adjacent one face of the gate when the latter is in closed position, which chamber, with the gate at or near closed position, has relatively free communication with the pressure zone adjacent the opposite face of the gate but restricted communication with the pressure zone adjacent said one face.

14. A furnace flue damper in accordance with claim 13, and in which the chamber is positioned at that side of the pivot axis providing for subjection of a portion of the gate area to pressure in opposition to opening movement of the gate.

HAL M. CUNNINGHAM.
